UNITED STATES PATENT OFFICE

96,897

DESIGN FOR A BRICK

Andrew Bowland, Mount Lebanon, Pa.

Application January 29, 1935, Serial No. 55,125

Term of patent 14 years

To all whom it may concern:

Be it known that I, Andrew Bowland, a citizen of the United States and a resident of Mount Lebanon (Pittsburgh), in the county of Allegheny and State of Pennsylvania, have invented a new, original, and ornamental Design for Bricks, of which the following is a specification, reference being had to the accompanying drawing, forming part thereof.

In the drawing:

Figure 1 is a top plan view of a brick, showing my new design;

Figures 2 and 3 are elevational views;

Figure 4 is a perspective.

A dominant or characteristic feature of this design is the appearance resulting from reducing the brick on all sides from a point intermediate its ends toward one end, and also from recessing two opposite side walls and at least two of the longitudinal edges.

I claim:

The ornamental design for a brick as shown and described.

In witness whereof, I have hereunto set my hand.

ANDREW BOWLAND.
